Primary Examiner — Lauren D McVey*Assistant Examiner* — Evin F Ershock(74) Attorney, Agent, or Firm — Salter & Michaelson(57) CLAIM

The ornamental design for a hair brush, as shown and described.

DESCRIPTION

FIG. 1 is a perspective view of a hair brush;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown in the drawing views depict portions of a hair brush that forms no part of the claimed design.
